UNITED STATES PATENT OFFICE.

STEVEN TOTH, OF LOS ANGELES, CALIFORNIA.

WELL-BORING TOOL.

1,347,469.

Specification of Letters Patent. Patented July 20, 1920.

Application filed March 11, 1919. Serial No. 281,928.

To all whom it may concern:

Be it known that I, STEVEN TOTH, a citizen of the United States, residing at Los Angeles, in the county of Los Angeles and State of California, have invented new and useful Improvements in Well-Boring Tools, of which the following is a specification.

This invention relates to well boring tools and pertains especially to tools of the under- 10 reamer type.

In the boring of wells, tools of both the revolving and reciprocating type are employed to drill the well hole in advance of the well casing, which is lowered into the bore following the tool as it advances in the boring operation. It is necessary to bore the well hole of a diameter not less than the outside diameter of the casing so that said casing may follow the tool, and in order 15 that this may be accomplished it is necessary that the jaws of the tool shall be allowed to spread to a distance of not less than the outside diameter of the well casing.

In the boring operation it becomes necessary to frequently resharpen the jaws of the tool, due to the nature of the work and the varying conditions of the earth, and in order 20 that the tool may be readily removed from the well without disturbing the well casing, provision is made to permit the jaws of the tool to collapse to a distance sufficient to enable the same to be drawn through the bore of the well tubing.

The object of my invention is to provide 25 a well boring tool, which will accomplish the foregoing recited requirements, and which may be operated to both expand and contract the boring jaws with the least possible difficulty.

40 A further object of my invention is to provide a well boring tool, whereby the jaws of the same may be operated to expand and contract by fluid under pressure, and controlled at the mouth of the well.

45 Other objects of my invention will appear in the following description and will be pointed out in the claim.

I have illustrated an embodiment of my 50 invention in the accompanying drawings, in which:

Figure 1 is a vertical section of a well bore and casing, showing my improved tool in operative boring position.

Fig. 2 is a similar view to Fig. 1 showing 55 the tool with the jaws collapsed and in the act of being withdrawn from the well casing.

Fig. 3 is an enlarged transverse section of the tool taken on the line 3-3 of Fig. 1.

Fig. 4 is a side elevation of the lower end 60 of the tool.

I have shown my invention as applied to the reciprocating type of tool which more specifically comprises the drill stock 7, adapted to reciprocate within the well casing 8 which is disposed in the well bore 9. 65 The stock 7 is preferably of cylindrical form and is provided with the centrally disposed annular bore 10 extending from the top to a point approximately midway of its length and communicating with the enlarged annular bore 11 which extends downwardly to the bottom of the stock.

The bottom of the stock 7 is provided with oppositely disposed grooves 12 and 13 in which are disposed respectively the cutting 75 jaws 14 and 15, which are loosely pivoted at their upper ends on the pivotal pins 16 and 17 which are secured in the wall of the stock 7.

The jaws 14 and 15 are provided with 80 the cutting points 18 and 19 and the outwardly inclined edges 20 and 21, said edges being adapted to engage with the lower inner edges of the well casing 8 when the tool is drawn upwardly through said casing. 85 The jaws 14 and 15 are also provided with the shoulders 22 and 23 adapted to engage with the lower edge of the stock 7 to receive the thrust when in action, the perforations 24 and 25 in the upper ends of said 90 jaws, through which the pivotal pins 16 and 17 pass, being of larger diameter than said pins. It will be seen by this construction that the pivotal pins are relieved of all strain and serve only to hold the jaws in 95 proper relation to the stock and as a hinge upon which said jaws may swing inwardly and outwardly as desired.

The jaws 14 and 15 are also provided with inwardly inclined surfaces 26 and 27 between which is interposed the conical end 28, of an annular piston 29, adapted to slide in the bore 11 of the stock 7. 100

The stock 7 is provided at its upper end with the threaded portion 30 to which is 105 threaded the extension tube 31, which is provided at its upper end with the threaded plug 32, said plug having an eye 33 to which is secured one end of a cable 34. The plug 32 is also provided with a boss 35 adapted 110 to receive one end of the flexible tube 36, the opposite end of said tube leading to a

source of fluid under pressure supply (not shown). A passage 37 arranged in the plug 32 opens communication between the extension tube 31 and the flexible tube 36.

5 The stock 7 has arranged in its side the relief valve 38 which is adapted to open communication between the passage 10 and the atmosphere, the operation and purpose of which will be hereinafter explained, and 10 comprises a seat 39, arranged in the stock 7, the valve head 40 having a stem 41, which engages in the guide 42 arranged in the plug 43 threaded into the stock 7, and interposed between the valve head 40 and the plug 15 43, and surrounding the stem 41 is the tension spring 44. The plug 43 is provided with the perforations 45 in order that the fluid may escape therethrough when the valve is unseated. It will be seen by the foregoing construction that the valve may be adjusted to 20 yield at any desired pressure from within the stock 7.

In the operation of my boring tool, the cutting ends 18 and 19 of the jaws 14 and 25 15 are first pressed together and then inserted into the top of the well casing. The tool is then lowered into the casing by means of the cable 34 until the cutting jaws strike the bottom of the well. Fluid under pressure is then admitted to the bores 10 and 11 30 of the stock through the tubing 36, which leads to a source of pressure supply (not shown). The fluid then acts on the piston 29 to force it downwardly, the conical end 35 28 thereof wedging between the inclined edges 26 and 27 of the jaws, thus causing said jaws to expand as clearly shown in Fig. 1 of the drawing. Power is applied to the cable 34 to reciprocate the same, 40 whereby the cutting points of the jaws are

caused to bore the well, the cable being from time to time revolved in order that a round hole may be bored.

When it is desired to remove the tool from the well, the fluid pressure is released from 45 above by means of a suitable valve (not shown) arranged adjacent the source of supply. The tool is then hoisted upwardly by means of the cable 34, the inclined edges 20 and 21 of the jaws engage with the lower 50 edge of the well casing and are forced together thereby, and at the same time the inclined edges 26 and 27 engage with the conical point 28 of the piston 29 and slightly lift the same.

65 In case that it should prove undesirable to release the pressure from above or that the attendant should fail to do so, the upward movement of the piston 29 will compress the fluid in the stock bore and thereby 60 cause the relief valve 38 to operate to relieve the pressure against the piston.

What I claim is:

A well boring tool comprising a stock 65 having a hollow bore, a piston mounted in said bore and adapted to slide therein, a plurality of cutting jaws pivoted adjacent the bottom of said stock and adapted to engage with said piston, means for admitting fluid under pressure to said hollow bore and 70 behind said piston, and a spring tension valve in said stock communicating with said hollow bore for automatically relieving the fluid pressure in said bore when said jaws start to contract.

75 In witness that I claim the foregoing I have hereunto subscribed my name this 15th day of February, 1919.

STEVEN TOTH.
